DISPOSABLE RAZOR WITH REINFORCED HEAD

Robert M. Eberbaugh, Charleston, W. Va.

Application May 3, 1954, Serial No. 427,291

2 Claims. (Cl. 30—47)

The invention relates to single service disposable razors and has for its objects to provide certain new and useful improvements in implements of this character.

An important object of the invention is to provide a disposable razor which may be integrally constructed of relatively thin paper, plastic or plastic-coated paper, as well as of any other comparative and readily obtainable economical materials, such for example as sheet aluminum.

The sheet materials of which the razor implement is formed may be readily heat sealed to secure the parts in position with sufficient rigidity in respect to the razor and handle, so as to obviate the necessity of employing separate reinforcing wires or other auxiliary materials.

A further object of the invention is to provide a single service razor which may be readily folded from a flat die cut sheet of the character described, and when assembled there is sufficient rigidity in the head and handle, as well as between these members, to enable the implement to be used for the purpose designed, after which it may be discarded or thrown away.

The economical single service razor constituting the present invention is preferably die stamped from a plastic sheet having characteristics which adapt it to high frequency sealing, thermo or heat sealing, or sealing by means of a suitable solvent. A simple folding and scoring process in which the plastic holds the shape of the folded or bent parts, results in a finished razor of small size and having inherent rigidity as a result of the peculiar manner of its integral formation in regard to the head and handle portion. The folded handle is of hollow tubular form, thereby providing adequate rigidity in the handle despite the relatively thin and flexible nature of the sheet material from which the integral unit is formed. The plastic material withstands hot water when the implement is put to use, and the metal blade portion of the razor is preferably coated with a thin plastic resin in order to form a perfect seal between the blade and the thin plastic sheet of which the razor proper is integrally constructed. Thus when heat is applied the blade is sealed to the plastic sheeting employed to construct the razor.

Numerous other objects and advantages of the instant invention will become apparent as it is better understood from the following description which, taken in conjunction with the accompanying drawings, is illustrative of a preferred embodiment thereof.

In said drawings:

Fig. 1 is a perspective view of the razor constructed from the integral blank illustrated in Fig. 4.

Fig. 2 is a side view of the razor.

Fig. 3 is a rear view.

Fig. 4 is a plan view of a die-cut paper or plastic blank from which the implement is constructed.

Fig. 5 is a perspective view of the blank in partially folded position in completing the razor.

Fig. 6 is a transverse section through the handle portion of the razor, taken on the line 6—6 of Fig. 2.

Fig. 7 is a plan view of a die cut blank similar to that

2

illustrated in Fig. 4 but showing a slightly modified form of the razor construction.

Referring to Fig. 4, the razor is preferably integrally formed from a rectangular paper, plastic or plastic-coated sheet 1 which is die cut into the configuration illustrated to include a pair of parallel elongated apertures 2 having a scored fold line 3 midway therebetween. The razor head portion A at the upper end of the blank is set off by a pair of spaced aligned die-cut slits 4 having a scored fold line 5 therebetween which connects the integrally formed razor head and handle.

The lower portion of the blank constitutes the razor handle B which is set off in part by a pair of spaced aligned slits 6, each slit terminating in an inwardly and upwardly scored fold line 7, respectively terminating at opposite ends of the scored fold line 5 connecting the head and handle.

Parallel longitudinal scored fold lines 8 are provided in the handle portion of the razor, to the end that the handle may be folded in the form of a hollow square having angular walls 9, two of which are overlapped and adhesively secured together. These overlapped adhesively secured walls are indicated at 9a in Figs. 5 and 6.

25 The described construction results in the provision between the slits 4 and 6, of a pair of complementary tab members 10 of generally trapezoidal configuration, said tabs being disposed between the handle and head portion of the razor when the latter is bent rearwardly along the scored fold line 5, and each of said tabs is foldable along one of the inclined score lines 7 for a purpose to be described.

35 The thin metal blade of the razor which may be of the "Schick" type is indicated at 11, and is preferably cemented to the head portion A² of the blank adjacent the lower slit 2 which is nearest the razor handle. As illustrated the metal blade 11 is affixed to the head portion so as to partially overlap the lower aperture 2 so that when the head portion is completed by folding along the score line 3, the sharp edge 11a of the blade is confined between the portions A¹ and A² of the head and the blade projects through the uppermost of the elongated registering apertures 2 to the proper extent for shaving purposes.

45 The overlapped portions A¹ and A² of the head are suitably cemented or heat sealed together at the rear of the head so as to confine the blade 11 therebetween, and the metal of the blade provides adequate transverse reinforcement of the razor head during packaging and 50 while in use.

After the metal blade member 11 is confined in the razor head portion, the head sheet sections A₁ and A₂ adhesively secured together, and the hollow tubular handle B has been folded and secured as described, the two complementary tab members 10 are bent or folded outwardly along the score lines 7 and adhesively secured or heat sealed to beneath the subjacent sheet portion A² of the head, as initially viewed in Fig. 5 and in final form in Figs. 2 and 3. The provision of these integral angularly extending tab members 10 provides adequate reinforcement for the razor head and holds the same rigidly with the handle against pivotal movement or "weaving" along the comparatively short score line 5 between the head and handle portions.

65 Before adhesively securing the tabs 10 beneath the adjacent head portion A², one outer projecting corner portion of each tab member is cut away and removed. This is to prevent such tab corner portions, indicated at 10b in Figs. 4 and 5, from extending beneath the registering apertures 2 through which the cutting edge of the blade projects. This will be more readily apparent from an inspection of Fig. 3 of the drawings.

The slightly modified form of razor integrally constructed from the single die cut blank of Fig. 7, is similar to the form hereinabove described with the exception that the tab members 10a for adhesively connecting the handle to the folded head portion are initially die cut and formed of substantially triangular configuration, rather than initially of substantially trapezoidal shape as shown in Fig. 4.

The single service disposable razor constituting the invention is well adapted to be packaged in a sanitary cellophane, paper or paper board carton together with a suitable amount of brushless or other shaving cream, contained in an aluminum foil or other plastic or paper bag or tube. This is for the purpose of permitting the implement to be conveniently dispensed in vending machines, for example at transportation terminals, sold over counters, or as a complimentary service of hotels, motels, steamships and the like.

The described procedure of constructing the razor from integral die cut plastic sheet material permits the instant throw-away razor to be practically made from sheets of plastic such as polyethylene or from a paper sheet coated or impregnated with plastic having characteristics suitable for sealings by present preferred manufacturing methods. Alternately thin aluminum sheets sealed by sweating, crimping or any other means, or any other inexpensive material which is adapted to die stamping, folding and sealing may be employed.

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

What is claimed is:

1. A razor comprising a head and a tubular handle integrally formed of flexible sheet material, and a blade having a cutting edge secured to said head, said head having a pair of parallel elongated apertures and having a reverse fold along a single fold line at one side edge thereof between said apertures to register the apertures

and to constitute an integral folded head of double thickness for confining said blade between said thicknesses, said blade projecting at its cutting edge through one of said apertures adjacent the line of fold of said head, 5 said handle constituting a hollow tube integrally connected to said head by a transverse fold line, and a pair of angularly extended tab members formed integrally with said handle and secured to the under surface of said folded head to rigidify the razor structure.

2. A razor comprising a head member having a pair of parallel elongated apertures therein and a tubular rectangular handle member integrally formed of die cut flexible sheet material, and a blade having a cutting edge secured to said head member, said head member including upper and lower integral sheet sections substantially parallel to each other and interconnected along a single line of fold at one side edge of the head member between said apertures to constitute an integral folded razor head of double thickness for confining said blade between said sheet sections, said blade having its cutting edge projecting through said elongated aperture in said upper sheet section of said head member adjacent said line of fold, 10 said handle member extending at an angle to said head member and comprising a hollow tube of square cross section having longitudinally extending side walls and integrally connected to said head member by a transverse fold line, and a pair of tab members each of substantially trapezoidal configuration formed integrally with and projecting transversely from the upper end of said tubular handle member on opposite sides thereof and secured to the lower sheet section of said head member to constitute a rigid connection between said head member and said handle member.
